BASKET LINING

Thelma J. Mellon, Kansas City, Mo.

Application December 31, 1936, Serial No. 118,511
Renewed April 17, 1939

1 Claim. (Cl. 5—93)

This invention relates to basket linings and more particularly to a lining for a baby basket having ornamental features in conjunction with a cover for the edges and interior of a basket on which the lining is mounted.

The principal objects of the present invention are to provide an ornamental lining for a baby basket; to provide a cover for the corners of the basket and inner body portion thereof for extension substantially over the bottom of the basket to protect a baby in the basket from contact with the rough edges thereof; to provide ties in conjunction with the lining for securing the lining to the basket; and to provide elastic means in conjunction with portions of the ties for maintaining the shape of the lining relative to the basket.

In accomplishing these and other objects of the present invention, I have provided improved details of structure, the preferred form of which is illustrated in the accompanying drawing, wherein:

Fig. 1 is a perspective view of a baby basket provided with a lining embodying the features of the present invention.

Fig. 2 is a vertical cross-sectional fragmentary view of the basket and lining on the line 2—2, Fig. 1.

Fig. 3 is a perspective view of a portion of the lining which is shown in flat condition to better illustrate its construction.

Referring more in detail to the drawing:

I designates a basket preferably of conventional shape having the usual bottom 2 and rim portion 3, the rim portion having a slightly larger perimeter than the bottom and being joined thereto by a wicker body portion 4 suitably curved to coincide with the bottom portion of the basket. Handles 5 are preferably mounted on the sides 6 and 7 of the basket rim in spaced relation to the curved end portions 8 and 9 of the basket on pivots which comprise pins 10 extending through the rim and handle portions, the pins having heads 11 and 12 for retaining the handle portions in pivotal position.

13 generally designates a lining for the basket which consists of a suitable fabric blank of generally rectangular shape having end edges 14 which are joined, as shown at 15 in Fig. 1, to shape the blank to the general contour of the interior of the basket. The lining may be colored to suit the taste of an individual employing the lining. The blank 13 is folded upon itself longitudinally substantially midway the length thereof, as at 16, and is provided with

double stitches 17 and 18 in spaced relation to the fold 16 to provide an encasement for a tie member 19. The lower end of the blank is hemmed, as at 20, Figs. 1 and 3, to provide an encasement for a tie member 21 similar to the tie member 19. The opposite side edge of the blank is folded upon itself, as at 22, and provided with double stitches 23 and 24 in spaced relation to the end thereof to provide an encasement for a tie member 25 for extension along the longitudinal side edges of the basket when the lining is in position thereon, as shown in Fig. 1.

In order to provide for placing the lining on the basket, the sides of the blank are slit, as shown at 26, and sewed, as at 27, to reinforce the same in such a manner that they provide splits in the fabric for fitting over the pins 10 on the basket between the basket rim portion and the handles.

The edges of the curved ends of the lining are provided with fastening devices, for example, the tie members 28 which are suitably fixed thereto at the split edges of the lining in substantial alignment with the tie members 25, it being obvious, however, that snaps, buttons, "zippers," or the like, may be provided to secure the edges of the slits together. Elastic members 29 are also provided which are mounted in a continuation of the encasement formed by the stitches 23, 24, that is in substantially contiguous relation to the tie members 28. The elastic members are of slightly less length than the distance around the curved ends of the basket and lining so that the material will be gathered in shirrs when the lining is placed in the basket to enhance the appearance of the lined basket. The tie members 28 provided at the edges of the slit 26 are adapted to be suitably united with the tie members 25, preferably in the form of the bows 30, to secure the lining on the basket.

In using a lining constructed as described, the main body portion of the lining, the ends of which having been sewed together, is placed in the interior of the basket on the bottom thereof, while the outer portions of the lining are laid over the edge of the rim, fitting between the handle portions and the rim of the basket by reason of the slits fitting over the pivot pins for the handle members and the elastic portions drawing the lining close to the outer body portion of the basket. The tie members 25 and 28 are then united in bows under such pivot points for securing the lining in position. It is apparent that the outer fold 22 forms a valance on the outer portion of the basket and the fold 16 forms 55

a valance on the upper inner portion of the basket to thus ornamenteally cover the basket and protect a baby in the basket from any rough edges of the basket. The ends of the continuous tie member 19 at the juncture of the lining edges are then suitably united for securing the central portion of the lining about the upper inner periphery of the basket. The ends of the tie member 21 are then secured together to draw the lower body portion of the lining toward the center of the bottom of the basket to partially cover the bottom portion of the basket.

What I claim and desire to secure by Letters Patent is:

15 In combination with a basket including a bottom, a body member having side and end walls, handle members, and spaced pairs of aligned members for pivotally mounting the handle members on the basket; a lining for the basket including a fabric blank having end portions and inner and outer side portions, the end portions being secured together to shape the blank to substantially correspond to the shape of the interior

of the basket, the outer side portion being provided with spaced pairs of slits aligned with the handle mounting members for adapting the lining to be positioned between the basket and handle members, spaced pairs of tie members on the outer side portion of the blank adjacent the slits thereof for adapting the blank to engage the exterior faces of the walls of the basket, a substantially continuous tie member on the inner side portion of the blank for adapting the blank 10 to substantially cover the bottom of the basket, a substantially continuous tie member on the blank between the inner and outer tie members to shirr the blank substantially at the upper interior faces of the basket walls for aiding in securing the lining to the basket and enhancing the appearance thereof, and spaced elastic members substantially contiguous to and interposed between portions of the outer tie member for adapting the blank to engage the exterior faces 15 of the end walls of the basket.

THELMA J. MELLON.
